UNITED STATES PATENT OFFICE.

ERNEST C. PRESCOTT, OF HAVERHILL, MASSACHUSETTS, ASSIGNOR TO PRESCOTT-ADAMS TABLE CO., OF HAVERHILL, MASSACHUSETTS, A CORPORATION OF MASSACHUSETTS.

COMBINED TABLE AND IRONING-BOARD.

1,131,954.

Specification of Letters Patent. Patented Mar. 16, 1915.

Application filed November 7, 1914. Serial No. 870,747.

To all whom it may concern:

Be it known that I, ERNEST C. PRESCOTT, a citizen of the United States, residing at Haverhill, in the county of Essex and State 5 of Massachusetts, have invented an Improvement in Combined Tables and Ironing-Boards, of which the following is a specification.

This invention relates to certain improvements in combined tables and ironing boards, and, more particularly, to certain improvements in the combined table and ironing board illustrated in my pending application, Serial No. 835,076, in which the ironing 10 board is pivoted at one end to the table frame and is adapted to be swung to a position below the table top, when the article is to be used solely as a table, and to be moved on its pivots to a position of use 15 over the top, where it is firmly supported by its pivots and by the top in parallel relation, and at a distance thereabove.

In the device disclosed in my said prior application, the ironing board may be held 20 adjacent one side only of the table, so that, if the article has been constructed for use by a person who is right-handed, it cannot be conveniently used by a person who is left-handed, and vice versa. Furthermore, in 25 said prior device the means for supporting the end section of the ironing board which is pivoted to the main section, did not support the same with the desired rigidity and it was somewhat inconvenient to move it 30 into position for use.

The primary object of my invention is to provide a simple and effective means, whereby the board may be laterally adjusted cross-wise of the table to different positions of 35 use thereover, so that the same device may be readily adapted for use by either right or left-handed persons.

A further object is to provide an improved means for supporting the ironing board, 40 and particularly the pivoted end section thereof.

I accomplish these objects by means shown in the accompanying drawings, in which;

Figure 1 is a side elevation of a combined 50 table and ironing board, embodying my invention, and showing the board in position of use. Fig. 2 is a longitudinal sectional view taken at the line 2—2 of Fig. 3, and showing the board folded beneath the table

top. Fig. 3 is a plan view. Fig. 4 is a sectional view on the line 4—4 of Fig. 3, showing the movable parts in raised positions. Fig. 5 is a cross-sectional view on the line 5—5 of Fig. 3. Fig. 6 is a cross-sectional view on the line 6—6 of Fig. 3. 55

As shown in the drawings, the table comprises the oblong frame *a*, supported by legs *b*, secured in the inner corners of the frame. A table top *c* is adapted to rest on the frame and is pivotally connected thereto by hinges *d* arranged at what is the left-hand end of the frame, when facing the same in the position of Fig. 1, said top being adapted to be swung upwardly from the frame to uncover the recess therebeneath, inclosed by the 60 frame. A spring-catch *e* is preferably provided between the top and frame, at the opposite end of the top from its hinges, to lock them together, and a brace *o* is connected to the top, at its front edge, to hold the top in 65 raised position, when desired, as shown in Fig. 4.

An ironing board is provided, which is divided transversely to form a main section *f*, and a somewhat tapering end-section *g*, 70 the abutting ends of said sections being connected by hinge-joints *h*, so that the end section may be folded back onto the upper side of the main section, as in my said prior device. A pair of cleats *i* are rigidly secured 75 to the under side of the main section *f*, and extend parallel to each other and to the longitudinal edges thereof, from a point adjacent its rounded end, to a point some distance beyond its abutting end, and legs *j* and *j'* are pivotally mounted between said cleats, 80 one beneath the main section and one at the projecting ends of the cleats, and each being adapted to be swung between a position in which it is perpendicular to the cleats, and 85 a position in which it is in the plane thereof. 90

The main section *f* is pivotally connected to the table frame, by means of a link *k*, which consists of a rigid rod bent to provide two end trunnions *k'*, which extend, in 95 axial alinement, into the right-hand table legs *b*, from their inner sides, at their upper ends, as indicated in Figs. 3 and 5, arm-section *k²*, which extend at right angles to said trunnions, arm-sections *k³*, which extend at 100 right angles to sections *k²*, and a horizontal pivot section *k⁴*, which connects said arm-sections *k³*, and extends in parallelism to the 105

axis of trunnions k' . Said section k^4 passes freely through apertures in the ends of the cleats i , adjacent the rounded end of the board, so that said board is pivotally mounted thereon. The length of said pivot section k^4 is sufficiently greater than the distance between the cleats, to permit the board to be slid transversely thereon between a position in which one cleat engages one arm-section 10 k^3 and a position in which the other cleat engages the other arm-section k^3 .

When the parts are in position for use as a table, the end section g will be folded onto the main section f and the cleats i will rest 15 on a supporting bar m , as shown in Fig. 3, the whole board thus being supported beneath the top.

When it is desired to use the ironing board, the table top is first released from the 20 frame and swung upwardly to the left, until it is supported in a nearly vertical position, by the brace o , as shown in Fig. 4. The top is thus held out of the path of movement of the board, which is then lifted and swung 25 upwardly to the right, so that it is raised above the level of the table, and swung back beyond a vertical position, the link k being at the same time, swung upward and then downward until the arm-sections k^2 rest 30 on the bottoms of the notches formed in the upper edge of the table frame, such portions of the frame acting as stops, or supports therefor. Said arm-sections k^2 will then be in horizontal positions and the sections k^3 in vertical positions, while the end 35 of the board may be swung into engagement with the side of the frame, so that it will be held in a nearly vertical position, as shown in Fig. 4. The top is then released 40 and lowered, so that it is returned to its normal position on the frame, the board being then held out of its path of movement. The legs j, j' are moved into positions perpendicular to the cleats, and then the board 45 is swung downward on the pivot section k^4 until said legs rest on the surface of the top, said legs and the link k acting to hold the board in a horizontal position. The end section g is then unfolded and swung down 50 onto the cleats i , which extend beyond the main section, so that they will act as a rigid support for said end section. It is noted that, while either or both legs j, j' , may be employed, it is generally preferable, if only 55 one is used, to use the one which is beneath the end section, as it supports the board with the greater firmness. The entire board will thus be rigidly supported on the table 60 top by the legs j, j' , and the link k , and the latter will, at the same time, hold the board from longitudinal movement.

With the above described construction, the board may be slid laterally on the pivot section k^4 in either direction from the middle position, in which it will be held, when

folded, to positions in which one side edge is directly over the adjacent side edge of the table top, that is, if it is to be used by a right-handed person, it will be moved to the lower dotted position of Fig. 3, and if by a left-handed person to the upper dotted position in the same figure. The board may, obviously be used in any intermediate position if desired, and will be moved to the middle position when it is to be folded beneath the top. 70 75

I claim:—

1. The combination of a table, an ironing-board pivoted thereon to swing about a transverse axis, and means to support the 80 board in a position of use directly over the table top, said board being transversely movable on its pivot, to permit lateral adjustment thereof over the top to different sides thereof, substantially as described. 85

2. The combination of a table, an ironing-board pivoted thereon at one end to be swung about a transverse axis to a position above the table top, means between the board and top to hold the board in parallel relation to 90 the top, while supported by its pivot, and means to permit transverse adjustment of the board over the top to permit the same to be held in a position of use adjacent either side of the table, substantially as described. 95

3. In combination with a table, an ironing-board, a pair of arms, pivotally connected at one end to the table to swing in axial alignment, and having a transversely extending pivot rod connecting the free ends 100 thereof, and an ironing-board pivotally mounted on said rod in transverse relation, to be supported thereby and to be adjusted transversely thereon to different positions of use over the table top, substantially as 105 described.

4. In combination with a table, an ironing-board, a pair of arms, pivotally connected at one end to the table, to swing in axial alignment, and having a transversely extending pivot rod connecting the free ends thereof, said pivot rod extending transversely of the table in parallel relation to its top, and to its pivotal axis, and arranged to be swung thereon to a position above the 115 top, an ironing-board pivotally mounted at one end on said pivot rod in transverse relation and laterally slidably thereon to different positions, and means between the opposite end of the board and said rod to support the board in parallel relation to the top in the different positions of transverse adjustment thereof, substantially as described. 120 115

5. In combination with a table, an ironing-board transversely divided to form abutting 125 and main and end sections, a hinge connecting said sections to permit the end section to be folded upon the upper side of the main section, a pivotal connection between the opposite end portion of the main section and 130

the table, to permit the board to be moved to a position above the table top, an arm rigidly connected to the under side of the main section and extending longitudinally thereof beyond its abutting end, to provide a support for said end section when in position of use, and a support connected to the end portion of said arm and arranged to engage the table beneath the end section to

support said sections in parallel relation to 10 the table top, substantially as described.

In testimony whereof, I have signed my name to this specification, in the presence of two subscribing witnesses.

ERNEST C. PRESCOTT.
